UNITED STATES PATENT OFFICE

2,076,210

COMPOSITE PIPE CONSTRUCTION

Jacob A. Stadtfeld, San Francisco, Calif., assignor
to Williams-Wallace Company, a corporation of
California

Application July 6, 1936, Serial No. 88,936

7 Claims. (Cl. 138—63)

My invention relates to an improvement in composite pipe of the type having an inner and an outer shell spaced apart from each other.

One of the objects of my invention is to provide a pipe having an inner and an outer shell, the inner shell being movable or slideable longitudinally with respect to the outer shell and means cooperating with said pipes for permitting while at the same time limiting the extent of said longitudinal movement.

Another object of my invention is to provide a positive interlock between said members.

Another object of my invention is to provide means between spaced walls of a two wall pipe structure in combination with a strip or ring type spacing means to hold said spacing means in correct longitudinal position.

Another object of my invention is to provide a form of spacing means between twin-walled piping having the minimum number of contacts with said walls which is geometrically possible.

Another object of my invention is to provide a novel form of spacing means composed of a substantially rigid polygonal ring member adapted to bear on its points against the outer tube and to contact the inner tube on its straight sides substantially intermediate the points.

Another object of my invention is to provide a novel form of rigid spacing member made up in laminated form, impregnated with cement and kiln dried.

Other objects and advantages of my invention will be apparent from the following description in which like reference numerals have been used 35 on corresponding parts in all the figures, and in which:

Fig. 1 is a view in perspective with the walls partly broken away to show the interior construction;

Fig. 2 is a cross-section view taken on the line 2—2 of Fig. 1;

Fig. 3 is a view in perspective of the spacing means;

Fig. 4 is a view in perspective of another form 45 of my invention; and

Fig. 5 is a cross-section view taken on the line 5—5 of Fig. 4.

This invention is an improvement on my prior Patent No. 2,013,193.

My invention provides a solution for the problem of positively locking the inner slideable tube within the outer tube and thereby making it impossible for the pipe to be installed in use with the inner tube removed, as it is possible to do with my earlier type. The present invention therefore produces a composite pipe which is safer and more acceptable to the fire underwriters and make it impossible for dishonest workers to slip out the inner pipe. It also obviates

the risk that in shipping and handling the inner tube will become dislodged and lost.

I shall now describe the construction of one section or unit of the pipe. In use, a plurality of these units are joined together to make the completed pipe. Each unit may be of any desired length.

The outer tube or shell 10 may be formed up from a flat sheet and joined by means of a lap joint 11. One end is crimped at 12 to form the male member of the joint and to give a reduced diameter to this end of the tube. Near its opposite end an internal annular ridge 13 is formed which may or may not extend all the way around the shell depending upon the designer's choice.

The inner tube or shell 15 is likewise formed up from a flat sheet and joined by means of a lap joint 16. One end is crimped at 17 to form the male portion of a joint. External annular ridges 18 and 19 or their equivalent are formed on the outer wall of shell 15. These are located in from the ends of the inner shell a distance which is determined in relation to the annular ridge 13 in the outer shell and the crimped end 12, respectively. This distance is determined by the length of the spacing member 20 plus the amount of longitudinal movement it is desired that the inner tube should have with relation to the outer tube,—usually three or four inches in each direction from a central position.

It is not necessary that the crimped end of the outer tube should have an external annular ridge 13, although it may be provided if desired, since the inwardly tapered end 12, being of reduced diameter, has the effect of holding the spacing member 20 within it.

The spacing member 20, (see Fig. 3) is shown in the form of a pentagon since that is the particular geometrical form adapted to fit the particular annular space formed between tube 10 and tube 15. The space between tube 10 and tube 15 for the most sizes of pipe is $\frac{1}{2}$ inch, therefore the larger the diameter of the pipe, the greater the number of sides necessary on the spacing member 20 for it to fit the space. It is one of the purposes of my invention to support and space the inner and outer tubes with relation to each other by members 20 having as few points of physical contact extending between the walls of each tube as is geometrically possible. This minimizes the heat conduction from one to the other and also allows a maximum air cell between the tubes.

I have found it preferable to make the spacer 20 of a laminated asbestos material,—usually about five layers wrapped from a continuous strip. When wrapped it is impregnated with a cement and then kiln dried. This causes it to become very hard and rigid in form, hence well adapted for my purpose. The sides 21 of the

member 20 are substantially straight and the corners 22 have a slight curvature. The longitudinal length of each member 20 is to be determined by the weight and size of the tubes 10 and 15, having in mind the strain of the load to be put on it. In the usual sizes, suitable for most household installations, I have found that an inch and a half to two inches is a suitable length. However, it may be longer or shorter according to the particular designer's choice, but in order to allow for the longitudinal sliding of the inner tube 10, the length should be less, for instance, than the distance between the internal annular flange 13 on the outer tube, and the external annular flange 18 on the inner tube.

The relative sliding of the inner tube within the outer is not only a convenience when joining together a plurality of units such as shown in Fig. 1, making it possible to inspect the joint of the inner tubes before sliding down the outer tube to complete its joint, but also to allow the inner tubes to adjust themselves to a tight fit at the joints independently of the outer tube so that both may come to a perfect seat at the joints. Also, the slideable feature is important since the temperature to which the inner tube is heated greatly exceeds that of the outer tube and therefore the former is subject to greater expansion and contraction than the latter. This is further accentuated by the fact that the present practice is to use aluminum for the inner pipe and galvanized sheet iron for the outer pipe.

In the modification shown in Figs. 4 and 5 the same principles apply as already explained, the only difference being that with the rectangular pipe the shape of the spacing member differs and the means on the inner tube, projecting into the annular spacing, instead of being a ridge like 18 and 19 of Fig. 1, is usually a piece of metal 30 welded to the inner tube and projecting over its ends 31 where it engages the sides 32 of spacing member 33. It may, however, be obtained in other ways and still be within the scope of my invention.

The ridge on the outer pipe corresponding with 13 of Fig. 1 may be formed by a swage as at 35, where it is adapted to be engaged by the side 36 of the spacing member. The location of the projections 34 and 35 is governed by the same conditions as was explained in connection with Fig. 1 and opposite ends are similarly crimped (not shown) to permit a plurality of the units to be joined together to form a long pipe.

The manner of assembling a unit of pipe is as follows:

Spacing members 20 are slipped on each end of a section of inner tube 15 with external annular ridges 18 and 19. This sub-assembly is then slipped inside the outer tube 10 from the uncrimped end. It will not slide out the other end because of the reduced diameter due to the crimping 12. The sub-assembly is then locked 65 inside the outer tube 10 by forming the internal ridge 13.

While I have shown one form of my invention, I want it clearly understood that it is capable of being embodied in other forms which would still retain the features of my invention and would represent differences from the described construction amounting only to the designer's choice.

I therefore claim my invention as follows:

1. A spacing member adapted for insertion between a pair of spaced walls, comprising a polygonal member formed from a plurality of layers of thin asbestos strips impregnated with a cement to form the same into a rigid one-piece whole. 5

2. In a composite pipe construction the combination of an outer shell, an inner shell spaced therefrom, both of said shells having spaced annular ridges formed thereon and projecting into the annular space between said pipes, and spacing means in said annular space adapted to hold said inner and outer shells in spaced annular relation to each other and to cooperate with said annular ridges to limit the relative longitudinal shifting of said inner shell within said outer shell. 10

3. In a composite pipe construction the combination of an outer shell having one end tapered inwardly, thereby restricting the opening therein and an internal annular ridge near the opposite end, an inner shell of smaller diameter than the aforementioned shell, having external annular ridges formed therein away from its ends, and spacing means inserted in the annular space between said pipes to hold them in spaced annular relation to each other and also to limit the longitudinal movement of the inner pipe by means of said annular ridges abutting 30 the edges of said spacing means. 20

4. In a composite pipe construction of the type having an inner and an outer shell arranged in spaced relation to each other, the combination of a continuous polygonal spacing means having substantially straight sides and contacting the walls of said pipes at the fewest number of points which is geometrically possible. 35

5. In a composite pipe construction the combination of an outer shell, an inner shell spaced therefrom, both of said shells having means thereon which project into the annular space between said pipes, and spacing means in said annular space adapted to hold said inner and outer shells in spaced annular relation to each other and to cooperate with the first-mentioned means to limit the relative longitudinal shifting of said inner shell within said outer shell. 40

6. In a composite pipe construction the combination of an outer shell, an inner shell spaced therefrom, both of said shells having spaced annular ridges formed thereon and projecting into the annular space between said pipes, and a pair of spacing means in said annular space adapted to hold said inner and outer shells in spaced annular relation to each other and to cooperate with said annular ridges to limit the relative longitudinal shifting of said inner shell within said outer shell. 55

7. In a composite pipe construction the combination of an outer shell having one end tapered inwardly, thereby restricting the opening therein and an internal annular ridge near the opposite end, an inner shell of smaller diameter than the aforementioned shell, having external annular ridges formed therein away from its ends, and a pair of spacing means inserted in the annular space between said pipes to hold them in spaced annular relation to each other and also to limit the longitudinal movement of the inner pipe by means of said annular ridges abutting the edges of said spacing means. 60
